DRILL FLUTING MACHINE

Harlan E. Matthews, Buchanan, Mich., assignor
to Clark Equipment Company, Buchanan, Mich.,
a corporation of Michigan

Application February 23, 1938, Serial No. 191,992

13 Claims. (Cl. 90—15.1)

This invention relates to a drill fluting mechanism, and more particularly is directed to apparatus of a semi-automatic nature for forming the flutes in small drill blanks and the like by the use of a single formed milling cutter in place of the two conventional formed cutters mounted angularly to each other and to the drill blank.

It has been difficult, in previous types of mechanisms for forming flutes in drills, to obtain accurate formation of these flutes due to the impossibility of producing two formed cutters of exactly the same contour and because of the inability of an operator to so adjust two cutters in angular relationship to each other and to the drill being cut as to produce a drill of absolute uniformity.

It has also been customary, so far as I am aware, to form the flutes in small drill blanks by means of hobs or the like, and the size of the blanks was such that inaccurate fluting occurred. So far as I am aware, no one has attempted to form such flutes by means of feeding a drill through automatic feeding mechanism to a rotating cutter with automatic means for indexing the drill so that the flutes are formed at predetermined portions of the blank.

The present invention contemplates, in its preferred embodiment, a mechanism which is self indexing and automatic in operation to the extent that after the drill blank has once been placed in the machine the mechanism itself will feed the blank to the milling cutter, returning the blank from the cutter, reindexing the same, again feeding it to the cutter and then again returning it from cutting position and declutching the drive mechanism. This therefore requires the attention of an operator only for the insertion of a drill blank into the mechanism, and the removal of the fluted blank therefrom. One operator is therefore capable of supervising the operation of a plurality of such mechanisms, which greatly reduces the cost of the drills.

One of the primary objects of the present invention is to provide means for gripping the drill blank in projecting position and then feeding the same along a predetermined helix whereby it is moved axially and simultaneously rotated as it passes into engagement with the cutter. A suitable clutch mechanism is provided for stopping the forward movement of the blank at a predetermined point and simultaneously raising the drill cutter out of engaging position. The blank is then returned, reindexed for the second flute and again fed into the cutter whereupon the clutch means again operates to return the blank

to initial position and simultaneously declutches the actuating means.

One of the features of the present invention is the provision of a lifting cam associated with the cutter for producing simultaneous raising movement of the cutter as the drill is fed thereto, thereby producing the desired decrease in depth of the flute as it approaches the shank portion of the drill. This same camming mechanism operates to raise the cutter out of engagement with the blank as the machine reverses for the re-indexing operation.

Another advantage secured by the present invention is the provision of a cutter so mounted with respect to the axial direction of the blank that the center of rotation of the cutter shaft always lies in a vertical plane through the axis of the blank, although the cutter itself may assume any desired angularity with respect to this blank.

Still another feature of the present invention is the provision of a clutch mechanism for clutching the blank feeding means to a prime mover such as an electric motor or the like, which is automatically disengaged upon the completion of a predetermined number of flute forming operations.

Still another feature of the present invention is the provision of a driving shaft mounted upon eccentric bearing journals and controlled by a friction clutch so that upon the feeding mechanism reaching its inward limiting position, the clutch is released to allow a half revolution of the shaft journals, thereby placing the shaft in a laterally offset position in driving engagement through a separate gear train to effect reverse movement of the feeding mechanism for withdrawing the blank from cutting position and re-indexing the same.

Still another object of the present invention is to provide a camming mechanism operable upon return of the feeding mechanism to initial position for releasing the indexing engagement employed in the first flute forming operation, and automatically reindexing the mechanism for forming the second flute.

Another feature of the present invention is the absolute uniformity of the completed drill, obtained by cutting each flute with the same cutter, thus producing two flutes exactly 180 degrees apart with the web or solid central portion of the drill in the exact center of the drill blank regardless of the setting of the cutter in relation to the drill. An advantage of the above feature is that owing to the uniformity of the amount of metal

removed from the flutes of the drills by the milling operation, they suffer much less distortion during the extreme high heats necessary in the hardening and drawing operations, with resultant saving in subsequent straightening operations.

Another feature and distinct advantage of the present invention is the provision of means for effecting relatively high speed reverse movement 10 of the feeding mechanism while yet effecting the proper relatively slower feeding speed during the flute forming operation.

In connection with this latter mechanism, I provide a second clutch operated by the feeding 15 mechanism as it reaches its outer limiting position for effecting a half revolution of rotation of the eccentric bearing journals of the main driving shaft, thereby restoring the original gear drive for producing inward movement of the feeding 20 mechanism.

Another feature of the present invention resides in the provision of a stop means operated by the feeding mechanism for de-energizing the entire machine in the event that the clutch for reversing 25 the movement of the feeding mechanism fails to operate.

Still another feature of the invention resides in the provision of a lubricating pump operated by the same prime mover that operates the feeding 30 mechanism, and which forces lubricant over the cutter and drill blank during the cutting operation.

Other objects and advantages of the present invention will be more apparent from the following detailed description which, taken in conjunction with the accompanying drawings will disclose to those skilled in the art the particular construction and operation of a preferred form of the present invention.

40 In the drawings:

Figure 1 is a rear perspective view of the essential portions of the drill fluting mechanism;

Figure 2 is a front perspective view of the mechanism shown in Figure 1;

45 Figure 3 is an end perspective view of the driving mechanism and feeding means;

Figure 4 is a diagrammatic view showing the gear relationships of various portions of the mechanisms; and

50 Figure 5 is a sectional view taken substantially on line 5-5 of Figure 4 showing the indexing mechanism.

Referring now in detail to the drawings, the base of the machine is shown generally at 10 and 55 mounted thereon is an electric motor 12 as shown in Figure 2. This motor is provided with the double pulleys 13 and 14 mounted on the drive shaft thereof, the pulley 13 being connected through the belt 15 to a large pulley 16 mounted 60 on the end of a shaft 17 which is supported in suitable journals 18 and 19 for rotation.

The operation of the motor 12 is controlled through means of the switch 20 shown in Figure 2 and mounted on a suitable pedestal 22 secured 65 to the base 10. Mounted on the shaft 17 is a small pulley 23 adapted to drive the belt 24 connected to the drive shaft 25 of a lubricant pump indicated generally at 26. The lubricant pump 70 has its inlet 27 connected to the base of the center supporting pedestal 28 and has an outlet connection 29 which, through the conduit 30 and valve 32, is adapted to supply cutting oil to the cutter 33.

From the cutter 33 the oil trips into the sump 75 34 from which it is drained through the spout

35 into the base of the stand 28 and then returns to the inlet of the pump 26. The shaft 17 extends through a clutch housing 36 and is provided with a small pinion gear 37 within the housing. The housing is also adapted to provide 5 a rotatable support for a countershaft 38 upon which is mounted the gear 39 driven from the pinion gear 37. A similar pinion 40 on the shaft 38 is adapted to drive back to the gear 42 which is free for rotation on the shaft 17. An 10 output shaft 43 extends through the opposite side of the housing 36 and is provided with a suitable clutch collar 44 connected to the clutch operating lever 45 for axial movement on the shaft 43 into and out of engagement with the clutch teeth 15 46 carried by the gear 42. Consequently, a double reduction of the drive from the shaft 17 to the shaft 43 is effected through the clutch 44 connected to the lever 45. The lever 45 is 20 mounted for rotation about a pivot 47 and at 25 its upper end is provided with a handle portion 48 adapted to be controlled by the operator. The lower end of the lever beneath the pivot 47 is provided with an ear 49 receiving one end of a tension spring 50, the opposite end which is secured to a fixed part of the stand 10 (not shown).

A suitable arm 52 is pivotally mounted on the top of the clutch housing 36 by means of the stud 53, and is provided with the spring 54 normally urging it against the lever 45 so that it follows the lever when the lever is shifted into clutch position. The arm 52 is held against reverse rotation about the stud 53 by means of the pivotally mounted latch 55 which has a lug 56 adjacent one end thereof adapted to engage in a suitable detent in the arm 52 to prevent reverse rotation thereof. A suitable leaf spring 57 normally holds the latch 55 in position to effect locking of the arm 52 against movement after the clutch has been shifted into clutch position. 40

The end of the shaft 43 is provided with the sprocket wheel 60 which is connected through the sprocket chain 62 to a second sprocket wheel 63 carried on the main driving shaft 64, as shown more clearly in Figure 3. Mounted on the outer 45 side of the sprocket wheel 60 is an idler arm 65 carrying the sprocket idler 66 for maintaining the proper tension on the chain 62.

The drive shaft 64 is mounted in eccentric bearing journals indicated most clearly in Figure 1 by reference numerals 67 and 68 which are normally held against rotation by means of a friction clutching mechanism enclosed in sub-base 71, the details of which form no part of the present invention, and therefore it is not believed necessary to describe the same. The bearing journals 67 and 68 are mounted in a support 71 which is secured to the frame 10 in any suitable manner, and the amount of eccentricity is indicated by the difference in position of the center of the bearing journals as indicated at A and A' in Figure 4. A suitable connector plate 69 connects the journals 67 and 68 of the eccentric bearing assembly so that they are rigidly supported for conjoint movement upon release of the friction clutching mechanism. A relatively small diameter driving gear of considerable axial extent is formed on the main shaft as indicated at 70, and rotates on bearings within the journals 67 and 68. Upon release of latches 65 and 167 by means of the friction clutch, the pinion gear 70 will rotate with the eccentric journals 67 and 68. Also secured to the main shaft 75 is a large gear drum 72 keyed for conjoint rotation therewith.

Referring now in more detail to Figures 3 and 75

4, it will be noted that when the pinion 70 is in a position such that its center is rotated, as indicated at A in Figure 4, the drum gear 72 is in meshing engagement with an idler gear 73 mounted upon shaft 74, which in turn meshes with an intermediate gear 75 mounted upon shaft 76 that, at its opposite side, is in meshing engagement with a drum gear 77 mounted on a shaft 78. The drum gear is adapted to rotate in the direction indicated by the arrow in Figure 4, and consequently produces clockwise rotation of the gear 77. It will be noted that the shaft 76 is supported on a suitable journal 79 and is provided adjacent its outer end with a bracket 79 adapted to support a pivot pin 80 mounting the latch releasing lever 82 thereon. The lever 82 is in the form of a bell crank, one end of which, indicated at 83, extends between the forked end lever 55. This same journal 79 extends downwardly and forms an end journal for the outer ends of the shafts 74 and 76 as clearly shown in Figure 3, and is also supported upon the base or frame 10.

When the gear member 72 is in its opposite position, that is, when its center is at a point indicated at A' in Figure 4, it is adapted to have meshing engagement with the indexing gear 85 carried on the spindle 86. It will also be noted that the gear 77 is at all times in meshing engagement with the feed gear 87 which is connected to a sleeve 88 extending through a longitudinally projecting journal 89 formed adjacent the top of the stand 28 as shown in Figures 1 and 2. The feeding sleeve 88 is provided with a spiral thread or recess 90, the pitch of which forms the lead for the blank. The sleeve 88 is moved longitudinally within the journal 89 by the engagement of a bronze pin therewith within the journal 89, the pin being formed at the end of the stud 92 which is supported in the boss 93 formed on one lateral side of the journal.

Considering now again Figures 1 and 2, it will be noted that the spindle 86 extends through the sleeve 88 and at its opposite end is provided with a collet portion 94 containing gripping jaws for gripping the drill blank 95. These jaws are actuated by the knurled spindle 96 at the opposite end of the collet 94 which is rotated in one direction to tighten the drill in position, and is rotated in the opposite direction to loosen the drill for removal.

Mounted on the frame 10 is a bar member 98 having an elongated slot 99 therein whereby it may be longitudinally adjusted with respect to the frame by means of the locking nut 100. The arm 98 has a vertically extending portion 102 which, at its upper end is provided with a pin 103 adapted to receive at the inner end thereof the camming arm 104 having the cam surface 105 secured thereto. This arm is mounted for pivotal movement with respect to the arm portion 102 and is normally restrained in the position shown in Figures 1, 2 and 3 by means of the tension spring 106 secured to the arm and to the arm portion 102.

The gear 85 is provided with two indexing plungers 107 and 108 mounted in cylindrical supports 109 threaded into suitable openings in the gear 85 and indicated in detail in Figure 5. The plungers 107 and 108 have reduced portions 110 projecting through the gear 85 and normally urged outwardly therefrom by means of the spring 111, outward movement of the plungers being limited by the screw 113 carried by the support 109 and engaging a suitable lip on the flattened surface of the projecting ends of the plungers.

The gear 87 is provided with a cooperating indexing plunger 114 mounted in a support 115 extending through the gear 87 and clamped thereto by the nut 116 engaging the projecting threaded shank. A suitable spring 117 retained in the axial recess in the support 115 normally urges the plunger 114 toward the gear 85. The projecting end 118 of the plunger 114, when in indexed position is adapted to extend into the recess or bore of one of the supports 109 and contacts the inner 10 end of the plunger 107.

However, when the rotation of the gear 85 is such as to force the projecting ends of either the plunger 107 or 108 inwardly by engagement with the cam surface 105 of the arm 104, the plunger 15 is forced inwardly into position to disengage the projecting end 118 of the plunger 114 from the gear 85. As a result, the gear 87 is released for relative rotation with respect to the gear 85, and the gear 85 is adapted to move into position to bring the opposite plunger opening thereof into alignment with the plunger end 118 of the plunger 114. Since cam member 104 swings back, this end immediately enters into the recess formed in the support 109 and thus locks the two gears 85 and 87 together for conjoint rotation into angular relationship of 180 degrees with respect to their initially locked position.

Whenever the two gears 85 and 87 are locked together the sleeve 88 will produce longitudinal movement of the spindle 86 upon rotation of the gear 87 since the spindle and sleeve are correspondingly locked together for conjoint rotation. Consequently, the longitudinal movement of the sleeve 88 will produce a corresponding axial movement of the drill blank 95, either into or out of engagement with the cutter 33.

Reference is now made to Figures 1 and 2 to show the mounting of the cutter mechanism for forming the fluted end in the drill blank. A post 40 (not shown) carrying the hardened drill guide (not shown) at its upper end extends vertically through the base 10 to the upper end (immediately below the drill bushing) to which is secured the sump 34 surrounding the cutter mechanism. This post has mounted thereon a sleeve 120 carrying at the lower end and integral with it the graduated flange 134 which is secured by clamping screws 135 to the base 10 but is otherwise free to rotate about the cutter post. Mounted upon sleeve 120 50 is the member 122 which has a sliding fit on sleeve 120 and is prevented from rotating with respect thereto by the key 132 which engages a slot (not shown) in sleeve 120. The member 122 is free to move axially on sleeve 120 but is normally 55 held in contact with cam bar 144 through the lateral extension 140 and the spring 143. Integral with the member 122 is the web 124 carrying at its lower end the transverse shafts 125 upon the opposite ends of which are mounted the pulleys 126. Adjacent to its upper end the web 124 provides a support for the longitudinally extending journal 127 through which extends the shaft 128 having the pulley 129 secured thereto above the pulleys 126. At its opposite end the shaft 128 is 60 provided with a suitable adjusting clamp nut for locking the cutter disc 33 in fixed position thereon by means of locking nut 130. The cutter is so positioned as to have its center disposed in the vertical center of the vertically extending cutter 70 post inside of sleeve 120, and consequently any rotation of the cutter mechanism will maintain the center of rotation of the cutter 33 in alignment with the center of rotation of the cutter post. In order to provide for adjustment of the cutting 75

angle of the cutter 33, the member 122 may be rotated with respect to the center line of the drill by loosening the clamp screws 135 in the flange plate 136 carried by the sleeve 120 and relocating the cutter mechanism by the angular graduations on the flange 134. The pulleys 126 and 129 are adapted to be engaged by a driving belt 137 which is trained thereof and which extends beneath the base plate 10 and under the pulley wheel 138 to the second pulley 14 on the motor drive shaft of the motor 12. Thus, the shaft 128 is driven from the motor 12 conjointly with the driving mechanism including the shafts 17 and 43.

It will be noted that the lower end of the member 122 is provided with a flange portion having the lateral extension 140 forming a pair of ears between which is clamped a lifting plate 142 normally engaged by a spring 143 for pulling the member 122, and consequently the shaft 128 downwardly to locate the same with respect to a cam plate or lifter 144. The lifter 144 is longitudinally tapered and is forced beneath the plate 142 by movement of the gear 87 to produce raising of the cutting mechanism as the feeding mechanism feeds the blank thereto so that the depth of cut of the flute is slowly decreased as the blank is fed into the cutter. The cam arm 144 is connected to a cross head 145 which has an extending shaft 146 supported by the journal (not shown) inside of the stand 28. The shaft 146 projects through a suitable journal inside of stand 28 and has a projecting end portion 150 adapted to be engaged by the lateral face of the gear 87. The projecting portion 150 is provided with a serrated surface on one lateral face thereof which is adapted to be engaged by the rocking surface of a locking member 152 in the form of a bell crank pivotally mounted on the side of the stand 28, and having its other arm portion extending down beneath the pinion and cross section 69 in such manner that when the eccentric bearings 67 and 68 are released so that the member 69 rotates to its lowermost position, it rocks the arm 152 into pressure engagement with the serrated surface of the shaft to lock the cam member 144 in fixed position against the tension spring 155 which is connected between the cross head 145 and a fixed portion of the mechanism.

50 Mounted on a bracket 156 projecting from the side of the stand 28 is a safety switch mechanism enclosed within the housing 157. This mechanism has a plunger 158 projecting therefrom toward the gear 87 and is adjustable with respect to the gear 87 by means of the adjusting screw 159 carried by an upwardly extending arm portion 160 of the bracket 156. This safety switch mechanism is for the purpose of shutting off the motor 12 if the gear 87 should move beyond a predetermined position determined by the length of flute to be cut in the drill blank. It will be noted from Figures 1 and 2 that a plunger 165 is provided projecting from the end face of the sub-base 171, and which is disposed in the path of movement of the gear 87. This plunger 165 is for the purpose of operating the friction clutch controlling the locking of the bearings 67 and 68 in alternate positions. When the gear 87 engages the plunger which forces the same slightly inwardly, the latch is released and the bearings 67 and 68 and member 69 rotate through a half revolution to move the pinion 70 out of engagement with the gear 87 and downwardly into position such that the gear drum 72 engages the gear 73. The return of the bearings 67 and

68 to their initial position is provided by engagement of the gear 87 with the adjusting knurled nuts 167 carried on a shaft 168 disposed out of the peripheral path of the gear 87 with the edge of the gear engaging the nuts 167 to move them to the left as shown in Figure 1, thereby drawing the shaft 168 to the left and consequently again releasing the friction clutch to allow the bearings 67 and 68 and the pinion shaft 50 to rotate through part of a second half revolution into almost their initial position, thereby placing the gear 85 in mesh with the gear drum 72.

Considering now the operation of the mechanism when it is desired to flute a gear blank, the motor 12 is first started by means of the control switch 20. This produces rotation of shaft 17 and also rotation of the cutter shaft 128 through the belt drives 15 and 137. A drill blank 95 has been locked in the collet 94 by rotation of the knurled locking spindle 96, and the mechanism is disposed with the sleeve 88 in its outermost position, that is, in the left hand position as viewed in Figure 1, or in the extreme right hand position as viewed in Figure 2. The gear 87 is locked to the gear 85 by the interengagement of the plunger 118 in the recess of the support 108 of the gear 85.

The clutch 48 is then rotated from the position shown in the drawings into a position to engage the clutch collar 44 with the clutch teeth 46 of gear 42. This produces rotation of shaft 43, and consequently, rotation of the sprocket wheel 63 in a counter clockwise direction. This produces counter clockwise rotation of the gear drum 72, and consequently, clockwise rotation of gears 85 and 87. The eccentric journals 67 and 68 are at this point in an intermediate position, with gears 70 and 87 out of engagement.

However, the gear 85 soon leaves the gear drum 72 due to the forward travel of sleeve 88 by engagement of the pin 92 in the thread 90. As a result, the eccentric journals move up to limiting position, rotating pinion gear 70 into mesh with gear 87 to drive the gear 87 for feeding the drill blank 95 into the cutter 33. During this time the pump 26 is pumping suitable lubricant over the cutter through the conduit 30, and this lubricant is being drained into the base of the stand 28 and returned to the pump. The gear 87 at the same time is in mesh with gear 77 and consequently rotates the gear trains 77, 75 and 73. However, since the drum gear 72 is out of engagement with gear 73, this gear train merely idles during the feeding operation. As the gear 87 nears the end of the feeding movement the lateral face thereof engages plunger 165 forcing the same inwardly, and thereby releasing the friction clutches holding bearings 67 and 68. These bearings are then free to rotate, and consequently rotate the pinion 70 and gear drum 72 into a position having a center of rotation indicated at A in Figure 4. As a result, driving engagement of the pinion with the gear 87 is released and no further feeding movement is produced.

During this feeding movement, the lateral face of the gear 87 has also been forcing the shaft 150 to the right as viewed in Figure 1, consequently forcing the cam 144 beneath the plate 142 to progressively raise the collar 122 and consequently decrease the depth of flute being cut. As the bearings 67 and 68 are released by the operation of plunger 165, the rotation of the pinion 70 and member 69 into the lower position rocks the bell crank 152 into position to engage the serrated

surface of the shaft 150 and thus locks the cam plate in position to maintain the cutter head in raised position. It should be pointed out that the rear portion of the cam bar 144 has an increased taper so that as the end of the feeding movement is reached, the cutter head is raised to an extent so as to remove the cutter entirely from the drill blank.

With the mechanism in this position, the rotation of the eccentric bearing journals into lowered position forces the drum gear 72 into engagement with the gear 73 and consequently drives the gears 75 and 77. This results in clockwise rotation of the gear 77 which, being in constant engagement with gear 87, produces counterclockwise rotation of gear 87, and moves the feeding sleeve 88 in the opposite direction to move the collet 94 and drill blank 95 back toward their initial position.

As the gears 85 and 87, which are still locked together in their initial position, move outwardly, the gear 85 moves into a position overlying the drum gear 72 but out of engagement therewith, and the engaged plunger 108 moves into engagement with the cam surface 105 which forces the plunger inwardly and thereby forces the plunger end 118 of the plunger 108 out of engagement with gear 85. At this instant, with the gear 85 released for relative rotation with respect to the gear 87, the gear 87 engages the nuts 167 to actuate control shaft 168 for releasing the eccentric bearing journal clutch and allowing the pinion shaft and drum gear to rotate back toward the position indicated at A' in Figure 4. As a result, the drum gear 72 moves into meshing engagement with gear 85, and rotates this gear in the opposite direction; that is, a counterclockwise direction, thereby bringing the plunger 107 into alignment with the plunger 118 whereby the plunger 108 moves into the opening in the support 109 of the plunger 107 to again lock the gears 85 and 87 together. During this time, the gear 85 is being driven by the drum gear 72 in a feeding direction, and due to the rotation of the gear 85, the plunger 107 moves into different alignment to produce the locked position indicated in Figure 5. At this instant the gear 85 drops off of the drum gear 72, allowing the eccentric journals to move into full upper position, and the mechanism feeds forwardly at a slow rate, being driven from the pinion 70 and the gear 87. The rotation of the bearings has also produced disengagement of the drum gear 72 from the gear 73 so that the gear 87 merely rotates the gears 77, 75 and 73 idly about the shafts as the feeding movement progresses.

It should also be remembered that as the eccentric bearing journals rotate from their lower to their upper position they release the lower end of the bell crank 152 which in turn disengages the upper portion of this bell crank from the serrated surface of the shaft 150, thereby allowing spring 155 to draw the cam bar 144 back to a position lowering the cutting mechanism into proper position for engaging the end of the drill blank. The mechanism then again feeds forwardly to form the second flute in the drill blank in the same manner as previously described.

As the plunger 165 is engaged by the gear 87, the bearings again rotate to their lower-most position, and the gear 87 is reversed and driven in a counter-clockwise direction by the gear 77 which is driven from the drum gear 72. However, this time when the plunger 107 engages the cam face 105 and thereby releases the locking engage-

ment by the gears 85 and 87, the return of the bearings toward their upper position produced by engagement of gear 87 with shaft 168 results in the pin 170 moving in a clockwise direction and engaging the upwardly extending portion 172 of the bell crank 82, thereby rocking the bell crank in a clockwise direction about the pivot 80 to lift the locking end of the lever 55 from engagement with arm 52. This releases the rocking engagement of the clutch 44, and the spring 50 is then effective to move the lever 45 back into the open position shown in Figure 1. This disengages the driving mechanism from the power shaft, and consequently stops the feeding mechanism so that the drill may be removed and a new drill inserted.

If, for any reason, the friction clutches controlled by the plunger 165 and shaft 168 should fail to operate and the feeding mechanism should continue feeding the drill toward the cutter, the gear 87 will engage the plunger 156, thereby breaking contact between the conductors enclosed within the cable 173 leading to the control switch 20 and will stop the motor 12 so that no damage to the mechanism will occur. This is merely a safety feature to prevent overdriving of the feed mechanism in case the friction clutches controlling the eccentric bearings should fail to operate.

It is therefore believed apparent that I have provided a mechanism which is automatic in operation after the drill blank has once been locked in position until completion of the fluting operation. Thus an operator is able to supervise the operation of a plurality of such machines since the only work required is the inserting and removal of the drill blanks, as the rest of the operations are all automatically controlled by the mechanism herein disclosed.

Of course I am aware that a number of changes may be made in certain details of construction of portions of the present mechanism without in any way departing from the underlying principles thereof, and I therefore do not intend to be limited except as defined by the scope and spirit of the appended claims.

I claim:

1. In combination, a rotating flute cutter, a spindle adapted to have a drill blank locked in one end thereof, a feeding sleeve surrounding said spindle, means for selectively indexing and locking said sleeve to said spindle for conjoint rotation therebetween to feed said blank to said cutter, and means for reversing the rotation of said sleeve upon predetermined feeding movement thereof.

2. In combination, in a drill fluting mechanism, a driving pinion and drum gear mounted on eccentric bearing means, feeding means driven in a feeding direction by said pinion, a train of gears normally in mesh with said feeding means, and clutch means engageable by said feeding means in one limiting position thereof for releasing said bearing means to move said drum gear into engagement with said train of gears to reverse the direction of movement of said feeding means and simultaneously moving said pinion out of engagement with said feeding means.

3. In combination, in a drill fluting mechanism, a main power shaft including a pinion and a drum gear mounted on eccentric bearing journals, feeding means driven by said pinion, reversing means driven by said drum gear, and clutch means controlled by predetermined movement of said feeding means for releasing said power shaft for movement on said journals to move said pinion into inoperative position and

- simultaneously to move said drum gear into operative position.
4. The combination of claim 3 further characterized in the provision of means operated by said drum gear at the end of reversing movement of said reversing means for reindexing said feeding means.
5. In combination, in a drill fluting mechanism, a blank holding spindle, a coaxial feeding sleeve mounted thereon, a rotatable cutter for fluting the blank in said spindle, means supporting said cutter for vertical movement relative to the axis of said spindle, driving means, indexing means interlocking said sleeve and spindle for feeding movement toward said cutter, and means controlled by movement of said sleeve for simultaneously raising said cutter to decrease the effective depth of said flute as the blank is fed thereinto.
6. In combination, in a drill fluting mechanism, a motor, a power shaft, feeding means for feeding a drill blank to a flute cutter, pinion means on said shaft for driving said feeding means, reversing means driven by said shaft and automatically operable to reverse said feeding means and reindex the same prior to a second feeding movement, means for clutching said motor to said shaft, spring means normally tending to disengage said clutch means, a latch for holding said clutch means in engaged position, and lever means actuated automatically upon the second reverse movement of said feeding means for releasing said latch to effect disengagement of said clutch means.
7. In a feeding mechanism for a drill fluting machine, a spindle having a collet at one end for gripping a drill blank, an indexing gear on said spindle having circumferentially spaced axially projecting spring pressed plungers, a feeding sleeve coaxially mounted on said spindle and having a spiral groove in the external surface thereof, a journal for said sleeve and spindle having a fixed pin engaging in said groove, a feeding gear fixed to said sleeve and rotated in one direction for feeding said sleeve through said journal, a spring pressed plunger on said feeding gear adapted to interlock selectively with said plungers on said indexing gear for locking said sleeve and spindle for conjoint rotation, and cam means selectively engaged by said spaced plungers on said indexing gear for indexing said spindle in different positions to said sleeve.
8. The combination of claim 7 further characterized in means for selectively clutching said feeding gear to a driving pinion and to a reversing train of gears to alternately feed said blank to a fluting cutter and to withdraw said blank from said cutter for reindexing said spindle with respect to said sleeve.
9. The combination of claim 7 further characterized in the provision of a drive shaft having a pinion for forward driving of said feeding gear and movable laterally of its axis on eccentric journals for declutching said pinion from said gear upon predetermined forward movement of said sleeve.
10. In a drill fluting machine, a motor, a cutter mounted on a horizontal shaft and driven from said motor, said cutter and shaft being vertically movable, a drive shaft, clutch means for connecting said shaft to said motor, means for feeding a drill blank horizontally to said cutter including interlocked coaxial gears, a pinion on said drive shaft for driving one of said gears, a drum gear on said shaft disposed out of engagement with the other of said gears during driving engagement of said pinion, an idler train of gears in constant engagement with said one gear, eccentric journals for said drive shaft, and means holding said drive shaft in one position in said journals and releasable upon predetermined movement of said feeding means for moving said drive shaft to a second position to disengage said pinion and move said drum into driving engagement with said train of gears for reversing the direction of rotation of said one gear.
11. The combination of claim 10 further characterized in the provision of cam means for disengaging said interlocked gears simultaneously with the return of said drive shaft to its first position to effect engagement of said drum gear with said other gear for reindexing said feeding means and interlocking said coaxial gears prior to a second feeding movement of said feeding means.
12. The combination of claim 10 further characterized in the provision of means on said other gear for releasing said clutch means upon the completion of the second reversal of said feeding means.
13. In combination, in a drill fluting mechanism having blank feeding means automatically driven in a feeding direction and then reversed to a non-feeding position, an indexing gear plunger means connecting said gear to said feeding means, cam actuated means responsive to final reversing movement of said feeding means out of feeding position for releasing said plunger means to release said indexing gear for rotation relative to said feeding means, and spring means engaging said plungers for reconnecting said gear after predetermined relative rotation into a reindexing position to said feeding means prior to initiation of the next feeding movement thereof.
